UNITED STATES PATENT OFFICE.

HERBERT W. KENWAY, OF NEWTON, MASSACHUSETTS, ASSIGNOR TO UNITED SHOE MACHINERY COMPANY, OF PATERSON, NEW JERSEY, A CORPORATION OF NEW JERSEY.

MACHINE FOR SETTING FASTENERS.

1,176,836.

Specification of Letters Patent.

Patented Mar. 28, 1916.

Application filed January 25, 1911. Serial No. 604,597.

To all whom it may concern:

Be it known that I, HERBERT W. KENWAY, a citizen of the United States, residing at Newton, in the county of Middlesex 5 and State of Massachusetts, have invented certain Improvements in Machines for Setting Fasteners, of which the following description, in connection with the accompanying drawings, is a specification, like reference characters on the drawings indicating like parts in the several figures.

This invention relates to machines for setting fasteners in sheet material and more particularly to machines for setting lacing 15 hooks in the uppers of boots and shoes, although certain features of the invention may be advantageously embodied in machines for setting eyelets, studs or other similar articles.

20 An object of the invention is to simplify the construction and improve the operation of hook setting machines as heretofore constructed.

To this end an important feature of the 25 invention consists in so organizing the various instrumentalities of a hook setting machine that a straight raceway may be employed for delivering the hooks from the hopper or magazine to the setting devices.

30 By eliminating all turns and branches from the raceway the possibility of a hook becoming misplaced so as to form an obstruction in traversing the raceway is obviated. The straight raceway has also an important 35 advantage from the manufacturing standpoint in that it may be produced easily and accurately and at relatively low cost.

In the machine herein disclosed, the raceway is inclined sufficiently to insure the 40 hooks sliding by gravity to its lower end and a hook carrier is disposed in substantial alinement with said raceway so that successive hooks may pass directly from the delivery end of the raceway to the anvil upon which they are subsequently set. After 45 a hook has been delivered to said carrier in its inclined receiving position said carrier is moved to a substantially horizontal setting position.

50 An important feature of the invention consists in the provision of a rotatable anvil within said carrier arranged to receive a hook edgewise from the raceway and turn

it about its axis into the position required for setting. One manner of effecting this 55 result consists in arranging the anvil so that it may be rotated bodily within the carrier during the movement of the carrier from receiving to setting position by a follower coöperating with a spiral guiding 60 member.

Another feature of the invention consists in arranging a hook holding clamp within said carrier in such a way that it shall be moved to engage a hook delivered to the 65 anvil in order to position and retain the same during the setting operation. As herein shown, the clamp is maintained in an inoperative position while the carrier is in its receiving position adjacent to the raceway 70 and as the anvil is rotated during its movement to setting position the clamp is gradually pressed into yielding engagement with the back of the hook by engaging with a spiral surface formed in the wall of the 75 carrier.

In order to insure precise operation of the machine in transferring hooks from the raceway to the carrier and also to adapt the machine for handling hooks of irregular 80 shape or non-uniform size, the present invention also contemplates positively acting transferring mechanism of a novel design. To this end a guideway is mounted adjacent to the end of the raceway and arranged 85 for movement toward and from the latter in order to carry a hook-engaging member which is mounted for reciprocation therein, into or out of the path of the hooks on the raceway. A separating fork coöperates with 90 the hook engaging and transferring member, being arranged to act upon the lowermost hook in the line on the raceway separating it from the other hooks and moving it into the path of the transferring member 95 which is then actuated to push the hook to its seat in the anvil.

Still another feature of the invention relates to the manner of feeding the work between successive setting operations. In 100 order to expedite the action of the machine and remove the clenched hook promptly from the carrier, so that the latter may be at once returned to its receiving position at the raceway, means are provided for effecting 105 a feeding movement of the work suf-

ficient to draw the hook out from the carrier immediately after the setting operation and before the main or principal feeding operation occurs. In the construction illustrated, 5 a combined upsetting die and punch is employed and the clenched hook is freed from the carrier by a transverse movement of this device while in engagement with the clenched hook. On the completion of this 10 movement the punching operation takes place and the principal feeding movement of the work is effected by moving the punch transversely prior to the setting operation.

Another feature of the invention relates 15 to the presser foot and mechanism for operating this element of the machine. Heretofore it has been customary to employ a separate cam for intermittently raising the presser foot during the feeding operation. 20 The desired results, however, are attained more simply, as herein shown by providing connecting mechanism between the presser foot and the punch or set-carrying member, whereby the presser foot may be raised 25 when the latter is moved into proximity to the work for punching, and held in inoperative position during the feeding operation.

These and other features of the invention will be best understood and appreciated 30 from the following description of a preferred embodiment thereof selected for purposes of illustration and shown in the accompanying drawings in which:—

Figure 1 is a view in side elevation of a 35 hook setting machine embodying the present invention; Fig. 2 is a view in front elevation; Fig. 3 is a view, partly in section, of the raceway separator, hook carrier, and upsetting die on an enlarged scale; Figs. 4 and 40 5 are detail views of the raceway separator; Figs. 6 and 7 are plan views of the hook carrier in two different positions; Fig. 8 is an enlarged view, partly in section, of the hook carrier in a position corresponding to that 45 shown in Fig. 7; Fig. 9 is a view in perspective of part of the hook carrier in a position corresponding to that shown in Fig. 7; Fig. 10 is a view in perspective of the presser foot actuating lever; Figs. 11 to 13 illustrate different steps in the cycle of the 50 machine.

The frame 2 of the machine may be of any suitable shape to sustain the moving parts. 55 As shown herein, it comprises a base plate, two uprights or standards and a connecting portion 3 extending between the upper ends of the standards. The standards are provided with journals for the main shaft 4 which is provided at its rear end with a 60 grooved driving pulley 6. The pulley 6 may be clutched to or unclutched from the shaft 4 by any suitable mechanism. The mechanism shown herein corresponds substantially to the clutch mechanism described 65 at length in United States Patent No.

934,066, granted on an application of George Goddu, to which reference may be had for details of construction. The present clutch, as in said patent, is unclutched by a cam 8 on the main shaft which acts through a cam 70 lever 9 and toggle links 10 at the proper point in the cycle of the machine and is actuated by springs, not shown, to clutch the driving pulley to the shaft when the toggle is broken by depressing the treadle rod 11. 75

The hook carrier is mounted on an angle lever 12 pivoted at 14 to a lug projecting upwardly from the upper portion 3 of the frame. The lever 12 is arranged to swing on the side of the portion 3 and at its forward end extends inwardly toward the center of the machine where it is provided with a cylindrical casing 16. Within the casing 16 is rotatably mounted a cylindrical anvil 18 having a hook receiving recess 19 formed in its upper surface. The anvil 18 is provided at its lower end with a spindle 20 carrying the arm 21, see Figs. 3 and 8. A spiral spring 22 extends between the spindle 20 and the casing 16 and serves to turn the anvil 18 in a clockwise direction. The position of the anvil is determined by a spiral controlling member 24 rigidly secured to the frame of the machine, the spring 22 serving to maintain the arm 21 in contact with said controlling member. The spiral controlling member 24 is so disposed that when the hook carrier is in its lower or hook receiving position, the arm 21 projects forwardly, in which position the hook receiving aperture 19 is 100 maintained in alinement with the end of the raceway. As the lever 12 is swung upwardly into hook setting position the arm 21 slides upwardly on the edge of the controlling member 24 and gradually turns the anvil 18 from the position shown in Fig. 7 through approximately 90° into the position shown in Fig. 6. 95

The casing 16 is provided with two passages one of which is in alinement with the end of the raceway and the recess 19 in the anvil 18 when the latter is in hook receiving position and the other of which extends laterally in alinement with the aperture 19 when the anvil 18 has been turned into hook setting relation. The hook therefore is delivered to the anvil 18 through the first mentioned passage and may be drawn out of the anvil 18, as will hereinafter appear, through the second of said passages. A yielding 110 clamping member 26, shown in Fig. 3, is pivotally mounted within the cylindrical anvil 18 and is normally pressed away from a hook in the cylinder by a leaf spring 27. The clamping member is provided on its rear side with a projecting lug 28 which, in the hook receiving position of the cylinder, projects into the wide end of a spiral recess 29 formed in the inner face of the casing 16, thus permitting the spring 27 to hold the 115 120 125 130

clamping member out of the path of a hook as the latter is being delivered to the cylinder 18. When the anvil 18 is rotated during the upward movement of the carrier the 5 clamping member 26 is gradually forced toward the hook as the lug 28 moves along the spiral wall of the recess 29 and when the anvil has been rotated into hook setting position the clamp is pressed yieldingly into 10 the depression in the rear side of the hook whereby the hook is prevented from moving during the setting operation. The engagement of the clamping member 26 with the hook, however, is not so firm as to prevent 15 its being displaced when the hook is moved laterally after the setting operation.

The lever 12 is actuated for setting the hook by means of a cam 32 on the main shaft 4 which acts on a cam roller carried by a 20 sliding bar 34 guided for reciprocation by bearing pieces 35 attached to the side of the portion 3 of the frame. The slide bar 34 at its forward end is provided with a head having a vertical slot in which is received a pin 36 projecting from the arm of the lever 12.

The hook supplying hopper and raceway 42 are mounted upon a bracket 44 which is supported at its rear end by a link 46 pivoted to the portion 3 of the frame and at its 30 forward end is pivoted to a cam lever 48. The cam lever 48 is pivoted to the frame at 49 and is oscillated by a cam 50 on the main shaft 4. The cam 50 is timed so as to move the delivery end of the raceway forwardly 35 into the position shown in Fig. 1 in which position a hook is transferred from the raceway to the anvil 18 and then rearwardly into the position shown in Fig. 3 while the upward movement of the lever 12 is taking 40 place. The hopper 40 may be of any suitable or well known type and preferably comprises a casing in which is mounted an apertured rotary separating blade 52 adapted to be rotated intermittently by a ratchet 45 wheel 54 and actuating pawl 56 mounted on the link 46. The pawl 56 is held in engagement with the ratchet wheel 54 by a spring 57. It will be seen that as the raceway and 50 hopper are moved rearwardly the pawl 56 will move upwardly engaging one tooth of the ratchet wheel 54 while, on forward movement of the hopper, the pawl 56 will be pulled downwardly thus rotating the separating plate 52. The raceway 42 for 55 the hooks extends without a curve from the hopper 40 to its delivering end, being twisted, however, through 90° so that the hooks delivered with their barrels in a horizontal position by the separating plate 52 will be 60 turned so that their barrels are in a vertical position.

Hooks delivered to the raceway slide by gravity until they are engaged by the separating fork 60 pivoted to a lug on the raceway, as shown in Fig. 4. The end of the

fork 60 is bent downwardly and is engaged by a pin 62 mounted in the arm 64 rigidly mounted on the portion 3 of the frame. It will be seen that as the raceway is moved forwardly the end of the fork 60 is held 70 against forward movement so that its operative end will be swung forwardly relatively to the raceway into the dotted line position shown in Fig. 4 thus separating a single hook from those on the raceway. A transferring member 66, having a portion 67 shaped to engage the head of a hook, is mounted for reciprocation in a movable guideway 68 mounted in a slot in the portion 3 of the frame, being held against longitudinal movement by a pin 69 but being slotted to permit a limited transverse or vertical movement. The engaging portion 67 is below the path traversed by the head of a hook during the first part of the movement 85 of the transferring fork 60 but means are provided for elevating the member 66 during the action of the separating fork so that the hook separated from those on the raceway may be engaged by the transferring 90 member and pushed from the raceway to the cylinder 18 when the raceway and cylinder are in proper relative position. To this end a wedge 70, which co-operates with a stationary wedge 71, is dovetailed into the 95 under surface of the guideway 68. The wedge 70 is provided with a rearwardly extending ear 72 which is slotted to receive a pin projecting from a downwardly extending lug 73 on the raceway. During the first 100 part of the forward movement of the raceway the pin traverses the slot in the ear 72 without affecting the wedge 70 but before the raceway reaches its delivering position the pin reaches the forward end of the slot 105 and thereupon shifts the wedge 70 forwardly elevating the slide 68 sufficiently to move the transferring member 66 into position to engage the hook which has been passed forwardly by the separating fork 60 and is 110 held near the end of the raceway by the spring detent 75. The transferring member 66 is then moved forwardly by the cam lever 76 pivoted to the portion 3 of the frame and actuated by the cam 77 on the main shaft 4. 115 As the raceway is moved rearwardly the spring 78 connected with the rear edge of the wedge 70 acts to retract this member whereupon the guideway 68 is depressed with respect to the raceway into a position 120 in which the transferring member 66 will not interfere with the action of the separating fork 60. In Fig. 3 the movement of the raceway is indicated as being substantially in a straight line as its departure from a 125 straight path at its delivery end is so slight as to be hardly noticeable in the relatively short movement which it has.

The upper set 80, which is provided with a central punching member, is mounted in 130

the forward end of a lever 82 pivotally mounted in a swinging head 84. The lever 82 is actuated in a vertical plane by the cam 86 acting through a vertical rod 87 carrying at its upper end a yoke 88 into which the rear end of the lever projects. The lever 82 is swung about the vertical axis of the head 84 to effect the feeding of the work, as will hereinafter appear, by means of a cam 90 acting through a vertical rock shaft 92 which is connected through suitable mechanism with the carrying member 94 formed integral with or otherwise rigidly secured to the head 84. The extent of the lateral movement of the lever 82 may be adjusted by the connecting mechanism interposed between the vertical rock shaft 92 and the carrying member 94. This connecting mechanism is not illustrated herein in detail as it forms no part of the present invention but it is disclosed in United States Patent No. 603,023 to Field to which reference may be had for further particulars. The cam 90 for effecting transverse swinging of the lever 82 differs from the corresponding cam of said patent in that it is arranged to impart to the lever 82 a slight movement toward the left after the setting operation has taken place, this movement serving to feed the clenched hook out of the hook carrier. This feature is of importance in that it permits the carrier to be lowered immediately after the setting operation, thus affording ample time for supplying the next hook to the carrier.

The machine is provided with a work table 100 which is apertured to receive the hook carrier and is provided at one side with a hardened cutting block 102 upon which the punching operation is effected. A presser foot 104 is mounted on the upper end of the rod 106, shown in Fig. 2, and is normally held in engagement with the work by a spring 108 bearing against the under side of the work table at its upper end and against the collar 109 at its lower end. A lifting lever 110 (see Fig. 10) is pivotally mounted on a bracket 112 at the rear of the work table and is arranged to engage under a lug projecting rearwardly from the presser foot. At its rear end the lifting lever 110 is provided with a curved cross piece 114 having a radius equal to its distance from the axis of the swinging head 84. At a point above the cross piece 114 the lever 82 is provided with a lug in which is mounted a small roller 115 which is adapted to engage the cross piece 114 and lift the presser foot whenever the lever 82 is depressed. When the lever 82 is depressed for punching the work in its extreme right hand position it will engage the cross piece 114 at some such point as that shown in Fig. 10 and during the transverse movement of the lever 84 the roller 115 will run

upon the cross piece 114 holding the latter depressed and the presser foot elevated while the feeding movement of the work is taking place. Means under the control of the operator are also provided for elevating the presser foot when work is to be presented to the machine. As shown in Fig. 2 the lower end of the rod 106 rests upon a transverse lever 118 pivoted to the front standard of the frame. An arm having a forwardly extending projection is pivoted on the same axis and is connected with an auxiliary treadle rod 121. By depressing the rod 121 the left end of the lever 118 is elevated and the presser foot raised from the work table.

The operation of the machine will be apparent from Figs. 2 and 11 to 13. In initial position the lever 82 is in its extreme right hand position with the punch 80 elevated. The presser foot 104 is elevated by the operator and the work presented to the machine and properly positioned with reference to gages, not shown. The treadle rod 11 is then depressed and the clutch allowed to engage the driving pulley with the main shaft. On rotation of the shaft the punch 80 is first depressed to the cutting block 102 to punch the work. It is then slightly retracted to relieve the pressure of the cutting block but not enough to disengage the work. During this time a hook has been delivered to the hook carrier which is in its hook receiving position, as shown in Figs. 2 and 11. The punch 80 is then moved toward the left feeding the punched hole into setting position as indicated in Fig. 11. Thereupon the cam 82 acts to swing the hook carrier upwardly forcing the barrel of the hook into the hole in the work and clenching it against the annular shoulder of the punch, the raceway, being retracted during this operation. During the setting operation, the punch, which now acts as an upsetting die, is again advanced very slightly approximately the distance which it was retracted at the beginning of the feeding operation. At the conclusion of the setting operation the punch is again retracted but not enough to disengage the clenched hook and it is then fed still further to the left as indicated by Fig. 13 whereby the clenched hook is drawn out of the hook carrier. Finally the punch is retracted from the work and moved toward the right to its initial position in readiness for a new cycle of operation.

Having thus described my invention, I claim as new and desire to secure by Letters Patent of the United States:

1. A machine of the class described having, in combination, an upsetting die, a co-operating swinging and turning anvil, power operated means for swinging the anvil, and means for turning the anvil during its swinging movement.

2. A machine of the class described, having in combination, an upsetting die, a co-operating anvil, and means for swinging said anvil about a transverse axis and simultaneously turning said anvil about its longitudinal axis.
3. A machine of the class described having, in combination, an upsetting die, a co-operating anvil, means for feeding a fastener to the anvil, means for bodily moving said anvil in the arc of a circle, and means for turning said anvil about the axis of the fastener.
4. A machine of the class described having, in combination, an upsetting die, a hook anvil, means for delivering a hook thereto, means for moving said anvil toward said upsetting die and simultaneously turning said anvil through a predetermined angle, and means for removing the clenched hook therefrom.
5. A machine of the class described having, in combination, a punch, means for moving the punch laterally after the punching operation to feed the work, a carrier movable to force the barrel of a hook over said punch in clenching the hook and means for thereafter moving said punch to effect a further feeding movement of the work.
6. A machine of the class described having, in combination, a setting device, a punch, and actuating means for moving the punch laterally while in engagement with its previously punched hole to feed the work to setting position, and for moving it while in engagement with the clenched fastener to impart a further feeding movement to the work after the setting operation.
7. A machine of the class described having, in combination, a carrier and an upsetting die, said upsetting die serving also as a punch, and means for actuating said upsetting die first to punch the work, then to set a fastener therein and thereafter to move the clenched fastener out of said carrier.
8. A machine of the class described having, in combination, a carrier for a hook, a member having a projecting end and means for moving said member first to engage the work and feed the same and then to engage a hook set in the work and impart a further feeding movement to the work while in engagement with the hook.
9. A machine of the class described having, in combination, a carrier having hook passages extending at an angle to each other, means for delivering a hook to said carrier through one of said passages, and a setting device operating to clamp a hook so delivered and then to move the clenched hook out of said carrier through said second passage.
10. A machine of the class described having, in combination, a setting device, a carrying lever therefor, a presser foot and means controlled by said carrying lever for moving the presser foot into inoperative position when the setting device is moved into operative position.
11. A machine of the class described having, in combination, a movable lever, a setting device carried thereby, an independently mounted presser foot and means interposed between said lever and presser foot for controlling the position of the latter.
12. A machine of the class described having, in combination, a lever carrying an upsetting die and punch, a presser foot normally held in engagement with the work and connections between said lever and presser foot so constructed and arranged that the latter is rendered inoperative when the lever is moved for the punching operation and maintained in such condition during the feeding and setting operations.
13. A machine of the class described having, in combination, a setting device, a punch-carrying member movable vertically to effect the punching operation and transversely to feed the work, a presser foot, and connections between said presser foot and said punch-carrying member so constructed and arranged that the presser foot is rendered inoperative by the punch carrying member during the transverse movement of said member.
14. A machine of the class described having, in combination, setting and punching devices, a carrying member therefor movable vertically to effect the punching operation and transversely to feed the work, a presser foot normally maintained in engagement with the work, a lever connected at one end to said presser foot and at the other end having a transversely extending portion, and a roller mounted on said carrying member and so disposed as to engage the transverse portion of said lever when the carrying member is moved vertically to effect the punching operation and roll upon said portion during the transverse feeding movement of said member.
15. A machine of the class described having, in combination, a hook carrier movable from hook receiving to hook setting position, and a hook holding clamp in said carrier movable gradually from an inoperative position, which it occupies when the hook is delivered, to a hook engaging position during the movement of the carrier.
16. A machine of the class described having, in combination, a hook carrier movable from hook receiving to hook setting position, a clamp shaped to engage the depression in the back of the neck of a hook, and means for moving said clamp from an inoperative position to an engaging position during the movement of said carrier.
17. A machine of the class described having, in combination, a carrier having a rotatable anvil, and a yielding hook clamp.

normally in an inoperative position, said carrier having a spiral surface formed therein whereby said clamp is moved into engaging position on the rotation of said anvil.

18. A machine of the class described having, in combination, a hopper for fasteners, a straight raceway extending therefrom at an inclination, a fastener carrier normally occupying an inclined position substantially in alignment with said raceway, means for moving said carrier from its inclined receiving position to a horizontal setting position and a setting device coöperating with 15 said carrier.

19. A machine of the class described having, in combination, a hopper for hooks, a straight raceway extending therefrom at an inclination, a hook carrier having an inclined receiving position in substantial alignment with the end of the raceway, means for transferring a hook from the raceway to the carrier, means for moving said carrier to a substantially horizontal 25 setting position, and a setting device coöperating with said carrier.

20. A machine of the class described having, in combination, a hopper for hooks, a downwardly inclined raceway extending 30 therefrom, a carrier having a recess for receiving a hook edgewise from said raceway, said carrier having an inclined receiving position in substantial alignment with said raceway, means for moving said carrier to a substantially horizontal setting position, means for turning a hook in said carrier through substantially 90° and an upsetting die coöperating with said carrier.

21. A machine of the class described having, in combination, an upsetting die, a coöperating carrier mounted for swinging movement about a stationary transverse axis, a reciprocatory bar connected with said carrier and movable to effect the upsetting 45 operation, and a cam for actuating said bar.

22. A hook setting machine having, in combination, a raceway arranged to deliver from its end a lacing hook in a position other than that in which the hook is to be 50 set, and means for moving the hook into the required position including a cylinder mounted for oscillation, a spindle associated with the cylinder, a torsion spring connected to the spindle and acting to turn the spindle to one direction, and means for turning the cylinder in the opposite direction.

23. A hook setting machine having, in combination, a raceway arranged to deliver

from its end a lacing hook in a position other than that in which the hook is to be 60 set, and means for moving the hook into the required position including a cylinder mounted for oscillation and having a hook engaging member, a spindle having its axis disposed coincident with the axis of the cylinder, a torsion spring connected to the spindle and acting to turn the spindle in one direction, and means for placing the torsion spring under tension.

24. A machine of the class described, having, in combination, an upsetting die, a hook carrying anvil, means for moving the anvil from hook receiving to hook setting position, and means for turning the anvil a predetermined distance about the longitudinal 75 axis of the hook to position the hook for setting.

25. A machine of the class described, having, in combination, an upsetting die, a hook carrying anvil, means for moving the anvil axially from hook receiving to hook setting position, and means for turning the anvil through a predetermined angle about the longitudinal axis of the hook during this movement to position the hook for setting.

26. A machine of the class described, having, in combination, an inserting device movable in a curved path, and means for feeding the work from and into setting position in two separate steps of definite extent, 90 both occurring between consecutive setting operations.

27. A machine of the class described, having, in combination, an inserting device movable toward and from the work, and a single tool movable for feeding the work both from and into setting position in separate steps of definite extent occurring between consecutive setting operations.

28. A machine of the class described, having, in combination, an upsetting die, a rotatable inserting anvil movable in a fixed path toward and from the upsetting die, and a spiral member co-extensive with the path of the anvil and constructed and arranged 105 to control the angular position of the anvil during its movement toward the upsetting die.

In testimony whereof I have signed my name to this specification in the presence of 110 two subscribing witnesses.

HERBERT W. KENWAY.
